UNITED STATES PATENT OFFICE.

HARRY F. ROACH, OF ST. LOUIS, MISSOURI.

MEANS FOR MAINTAINING A GIVEN DIRECTION OF ROTATION OF SHAFTS.

SPECIFICATION forming part of Letters Patent No. 656,422, dated August 21, 1900.

Application filed June 5, 1899. Serial No. 719,488. (No model.)

To all whom it may concern:

Be it known that I, HARRY F. ROACH, a citizen of the United States, residing at the city of St. Louis, State of Missouri, have invented a certain new and useful improvement in means for maintaining a given direction of rotation of a shaft whose power is supplied by a shaft susceptible of revolving in either of two directions, of which the following is a full, clear, and exact description, such as will enable others skilled in the art to which it appertains to make and use the same, reference being had to the accompanying drawings, forming part of this specification, in which—

15 Figure 1 is a top plan view of my improved means for maintaining a given direction of rotation of a shaft or sleeve whose power is supplied by a shaft susceptible of revolving in either of two directions. Fig. 2 is a vertical longitudinal sectional view of the same, taken on the indicated line 2 2 of Fig. 1; and Fig. 3 is a detail horizontal sectional view of the laterally-movable clutch-gear, together with its coöperating elements.

25 This invention relates to a new and useful improvement in means for maintaining a given direction of rotation of a shaft whose power is supplied by a shaft susceptible of revolving in either of two directions, and has 30 for its object to provide said means in a positively-simple and effective manner.

This device is designed particularly for use in connection with a dynamo or motor suitably mounted upon a vehicle wherein if a dynamo 35 is employed for generating an electric current for any purpose whatever the armature of said dynamo will be caused to rotate in a given direction regardless of the direction in which the vehicle is traveling or, in other 40 words, regardless of the direction in which the power-shaft which drives the armature is revolving. If a motor is employed for driving the vehicle, the object of this invention is to drive the vehicle in either of two directions 45 and still permit the motor to run in one direction.

The essential features of this invention reside, first, in the construction and arrangement of the clutch-gear and its coöperating 50 means, whereby a shaft is caused to rotate in one direction only while its companion-shaft,

which is either a driving or a driven shaft, is caused to rotate in either of two directions.

Other features of the invention reside in the construction, arrangement, and combination 55 of the several parts, all as will hereinafter be described and afterward pointed out in the claims.

Like letters of reference refer to like parts throughout the several views. 60

In the description to follow I will describe this device as coöperating with a dynamo; but I do not wish to be understood as limiting myself to the same, as a motor or even a pulley to be driven in one direction will come 65 within the scope of this my present invention.

In the drawings, A represents a supporting-frame, which may be the framing of a locomotive or other vehicle, as is obvious, upon which is mounted my present invention. 70

B indicates the main shaft or axle of the vehicle, which is journaled in the frame A in any suitable or usual manner, said axle being provided with the usual wheel b.

C indicates a dynamo whose armature is 75 supported on a hollow shaft or sleeve c, which sleeve is designed to rotate upon and is supported by an axially-arranged shaft c', suitably journaled in the frame A.

D indicates a spur-gear suitably keyed or otherwise secured to the axle B and is designed to mesh with a laterally-movable pinion or clutch-gear E, arranged on the shaft c'. Pinion E is provided with a female screw-threaded axial bore e, designed to engage and 80 coöperate with a male screw-thread c'', formed on the shaft c', whereby when said pinion is caused to rotate the cooperation of its female threaded bore e with the male thread c'' of the shaft c imparts lateral movement to said 85 pinion. (See Fig. 3.) Shaft c is provided at its end next adjacent to the pinion E with an enlarged flange c''', so distanced from said pinion that a slight lateral movement of the same will cause its nearest side to contact 90 with said flange c''', thereby establishing a friction-clutch and causing the shaft c, carrying the armature, to rotate in the same direction as does the aforesaid pinion E.

F indicates a spur-gear loosely mounted 100 upon the shaft c', being arranged on the opposite side of pinion E to that upon which

the shaft *c* and its carried flange *c'''* is located. This spur-gear *F* meshes with a spur-gear *G*, loosely mounted upon a suitable stud-shaft secured to the frame *A*, said spur-gear *G* in turn meshing with another spur-gear *H*, secured to a shaft *h*, journaled in said frame *A*.

I indicates a spur-gear secured to the shaft *h*, the same being preferably located at the opposite end of said shaft to that upon which 10 the spur-gear *H* is located, said spur-gear *I* being in mesh with a spur-gear *J*, secured to the armature-bearing shaft *c*. Suitable ball-bearings may be employed wherever desired—as, for instance, as is illustrated at *x*—to relieve the friction caused by the end thrust of 15 the clutch-gear *E*.

From the description above given and a glance at the accompanying drawings it is obvious that the armature mounted upon the 20 shaft *c* is caused to rotate always in one direction, although the shaft or axle *B* may rotate in either of two directions, viz: when the axle *B* is rotating in the direction indicated by the arrows in full lines, (see Fig. 2), the 25 clutch-gear *E* will by virtue of the right-hand screw-thread move laterally on its shaft *c'* in the proper direction to cause the side nearest the flange *c'''* to contact therewith, thereby causing said shaft *c* to rotate in the same direction as does said friction-gear. When the 30 axle *B* is caused to rotate in the direction indicated by the dotted-line arrow, the clutch-gear moves laterally on the shaft *c'* in the proper direction to contact with one side of the spur-gear *F* and by frictional contact 35 causes said gear *F* to take up the same direction of rotation as does said clutch-gear, which is now the opposite direction to that before referred to or illustrated by the full-line arrow; but through the instrumentality of the 40 differential gearing—*i. e.*, the three spur-gears *F*, *G*, and *H*, as compared with the two spur-gears *I* and *J*—the armature-bearing shaft *c* continues to rotate in the direction in which 45 it did when the axle *B* rotated in the opposite direction, as will be readily understood.

I am aware that minor changes in the construction, arrangement, and combination of several parts of my device can be made and 50 substituted for those herein shown and described without in the least departing from the nature and principle of my invention.

Having thus described my invention, what I claim, and desire to secure by Letters Patent, is—

1. In a device of the character described, the combination of a gear *D* susceptible of rotation in either of two directions, a member designed to rotate in one direction only, a shaft 60 concentric with the axis of said member, a clutch-gear on said shaft, means for imparting lateral movement to said clutch-gear on said shaft, said clutch-gear being constantly in mesh with said first-mentioned gear, and 65 means coöperating with said clutch-gear for causing said member to rotate in the same di-

rection irrespective of the direction of rotation of said gear *D*, substantially as described.

2. In a device of the character described, the combination of the shaft *B*, which is susceptible of rotating in either of two directions, a hollow shaft *c* which is designed to rotate in one direction only, a shaft *c'* located within said hollow shaft, a clutch-gear provided with a bore, a female screw-thread formed in the bore of said clutch-gear, a male screw-thread formed on a shaft *c'*, for coöperation with the female screw-thread of the clutch-gear, a spur-gear on the shaft *B* constantly in mesh with said clutch-gear, a flange arranged on the 80 hollow shaft *c*, said flange forming one member of a clutch, the other member of said clutch being that side of the clutch-gear next adjacent to said flange, whereby, when said clutch-gear is forced against said flange, a 85 clutch will have been established, a spur-gear *F*, mounted upon the shaft *c'*, one side of said spur-gear *F* serving as one member of a clutch, the other member of said clutch being that side of the clutch-gear next adjacent to said flange, whereby, when said spur-gear *F*, and gearing coöperating with said spur-gear *F* and said hollow shaft *c*, substantially as, and for the purpose specified.

3. In a device of the character described, the combination with a shaft or axle *B*, of a 95 spur-gear *D* arranged on said axle, a clutch-gear *E* in mesh with said spur-gear, a screw-threaded bore formed in said clutch-gear, a shaft *c'*, a screw-thread formed on said shaft *c'*, designed to mate and coöperate with the screw-threaded bore of said clutch-gear, a hollow shaft *c* surrounding said shaft *c'*, a spur-gear *F* arranged on said hollow shaft *c*, a spur-gear *J* arranged on said shaft *c*, a shaft *h*, a spur-gear *H*, arranged on said shaft *h*, a spur-gear *I* arranged on said shaft *h*, said spur-gear *I* being in mesh with the spur-gear *J*, and an intermediate spur-gear *G*, suitably mounted, and in mesh with the spur-gears *F* and *H*, all substantially as, and for the purpose specified.

4. In combination with the frame of a vehicle, an axle *B*, which is susceptible of rotating in either of two directions, a hollow shaft *c* which is designed to rotate in one direction only, a shaft *c'* located within said hollow shaft, a clutch-gear provided with a bore, a female screw-thread formed in the bore of said clutch-gear, a male screw-thread formed on the shaft *c'*, for coöperation with the female screw-thread of the clutch-gear, a spur-gear constantly in mesh with said clutch-gear, a flange arranged on the hollow shaft *c*, said flange forming one member of a friction-clutch, the other member of said friction-clutch being that side of the clutch-gear next adjacent to said flange, whereby, when said clutch-gear is forced against said flange, a friction-clutch will have been established, a spur-gear *F*, loosely mounted upon the shaft *c'*, one side of said spur-gear *F* serving as one member of a friction-clutch, the other mem-

ber of said friction-clutch being that side of the clutch-gear next adjacent to said spur-gear F, and gearing coöperating with said spur-gear F and said hollow shaft c; substantially as, and for the purpose specified.

5. In combination with the frame of a vehicle, an axle B, a spur-gear D arranged on said axle, a clutch-gear E in mesh with said spur-gear, a screw-threaded bore formed in 10 said clutch-gear, a shaft c', a screw-thread formed on said shaft c', designed to mate and coöperate with the screw-threaded bore of said clutch-gear, a hollow shaft c surrounding said shaft c', a spur-gear F arranged on 15 said shaft c', a spur-gear J arranged on said shaft c, a shaft h, a spur-gear H, arranged on said shaft h, a spur-gear I arranged on said shaft h, said spur-gear I being in mesh with the spur-gear J, and an intermediate spur- 20 gear G, suitably mounted, and in mesh with the spur-gears F and H, all substantially as, and for the purpose specified.

6. The herein-described clutch mechanism, consisting of the following elements, a shaft c', 25 a screw-thread formed on said shaft, a clutch-gear provided with a screw-threaded bore designed to coöperate with the screw-thread formed on the shaft c', a hollow shaft c, surrounding said shaft c', a flange formed on said 30 hollow shaft, a spur-gear F arranged on said shaft c', said flange and said spur-gear F being arranged on opposite sides of said clutch-gear, means for rotating said clutch-gear, which rotation, through the instrumentality 35 of the screw-threaded bore, and the screw-thread on the shaft c', causes lateral movement of said clutch-gear, and causes the same to contact with either the flange on the hollow

shaft or the spur-gear F, thereby effecting a friction-clutch and causing either said flange 40 or said spur-gear F to rotate in the same direction as does said clutch-gear, and means coöperating with said spur-gear F and said hollow shaft for causing said hollow shaft to rotate in the same direction when the clutch- 45 gear contacts with the spur-gear F, as does the hollow shaft when said clutch-gear contacts with the flange on said hollow shaft; substantially as described.

7. In a device of the character described, 50 the combination of a gear susceptible of rotation in either of two directions, a member designed to rotate in one direction only, a shaft concentric with the axis of rotation of said member, a clutch-gear on said shaft, co-acting parts on said shaft and clutch-gear 55 for imparting lateral movement to said clutch-gear on said shaft, said clutch and first-mentioned gear being constantly in mesh, a part adapted to be engaged by said clutch-gear 60 when rotated in one direction to rotate said member in the same direction, a gear adapted to be engaged by said clutch-gear when rotated in the opposite direction, and gear connections between said last-mentioned gear 65 and said member for rotating the member in a direction opposite to the direction of rotation of said clutch-gear, substantially as described.

In testimony whereof I hereunto affix my 70 signature, in the presence of two witnesses, this 3d day of June, 1899.

HARRY F. ROACH.
